GARMENT HANGER

Jack M. Zuckerman, Elmhurst, N.Y., assignor to Yankee Plastics, Inc., New York, N.Y., a corporation of New York

Filed June 30, 1961, Ser. No. 65,768

Term of patent 14 years

(Cl. D80—8)

FIG. 1

FIG. 3

FIG. 1 is a front elevation of a garment hanger, showing my new design,

FIG. 2 is a side view, and

FIG. 3 is a cross-section of FIG. 1 taken along lines 3—3.

I claim:

The ornamental design for a garment hanger, substantially as shown.
